(57) **CLAIM**

The ornamental design for a window lock, as shown and described.

DESCRIPTION

1.1 is a front view of the first element of the window lock;
1.2 is a back view of the first element thereof;
1.3 is a right view of the first element thereof;
1.4 is a perspective view of the first element thereof;
1.5 is a front view of the second element view thereof;
1.6 is a left view of the second element thereof;
1.7 is a combination view of the first element and the second element of the window lock;
1.8 is a left view of the first element thereof;
1.9 is a top view of the first element thereof;
1.10 is a bottom view of the first element thereof;
1.11 is a back view of the second element view thereof;
1.12 is a right view of the second element view thereof;

(Continued)

1.13 is a top view of the second element view thereof;
 1.14 is a bottom view of the second element view thereof;
 1.15 is a perspective view of the second element view thereof.

1 Claim, 15 Drawing Sheets
